UNITED STATES PATENT OFFICE.

FREDERICK O. HILFIKER, OF ILION, NEW YORK.

WATER-CLOSET.

No. 902,295.

Specification of Letters Patent.

Patented Oct. 27, 1908.

Application filed July 1, 1907. Serial No. 381,678.

To all whom it may concern:

Be it known that I, FREDERICK O. HILFIKER, a citizen of the United States, residing at Ilion, in the county of Herkimer and State of New York, have invented certain new and useful Improvements in Water-Closets, of which the following is a specification, reference being had therein to the accompanying drawing.

10 My invention relates to an improved water closet, and I declare that the following is a full, clear, concise and exact description thereof, sufficient to enable one skilled in the art to make and use the same,

15 reference being had to the accompanying drawings in which like letters and numerals refer to like parts throughout.

Among the particular features of my invention is that it comprises a minimum number of parts, the several members being integral so far as possible and so constructed as to be assembled without the necessity of washers, the said parts being largely or altogether of cast members so that I avoid all 25 machine work on the device.

Another feature is that there can be no leakage save that occasioned by overflow.

Further details of the invention will appear from the following specifications and 30 the drawings.

In the drawings Figure 1 is a sectional view on the medial front to rear line; Fig. 2 is a front view of the upper part or tank portion, certain parts being broken away to 35 show the interior members, and Fig. 3 is a horizontal sectional view on the line $x-x$ of Fig. 1.

Referring to the drawings in detail, the device comprises water-tank A and bowl portion B which can be of any suitable style. The portion designated by the general reference as A comprises a tank, which I prefer to make of porcelain or other suitable material, having the walls 1 and 2 together 45 with end walls—not shown. The front wall 2 has a bore from bottom to top, the interior portion of the wall not extending however to the top of the other portions, the said bore being indicated by 3 and provided for vertical play of the operating rod 4 which has a handle 5. This bore also serves as an overflow, its lower outlet opening into a receptacle connected with the closet portion.

The back wall, 1, has two or more holes well 55 above the water level, so that through these holes I can insert screws or other fastening

device and thereby fasten the tank to the wall. In the interior of the tank A is formed a siphon with long arm 7 having its lower end enlarged, as hereafter pointed out, 60 and the short arm 8. 9 represents a short pipe connected to the short arm of the siphon adjacent its top and extending nearly to the bottom, the purpose of which is to admit air after the operation of the closet. 65 The tank A and the siphon members, as above described, are formed with a rim at the lower portion to rest upon the top of basin or bowl portion B, the rim of the tank portion overhanging the rim of the bowl 70 portion, as clearly seen in Fig. 1.

The bowl portion B is shown as integral, consisting of the front portion which is of the usual commercial form and of the general character, as indicated in Fig. 1, and 75 the rear upward extending portion designated as 10 terminating in a flat edge for the support of the tank members with the siphon. Supported in the upright portion 10, as by a bracket 11, is an annular cup 12 80 adapted to hold water and into which the enlarged end 13 of the siphon extends reaching substantially to the bottom of the cup. Within the annular interior space of the cup, shown as 14, is a cylindrical valve member 15 which consists of a pipe which may be made of metal, but which I prefer to make of porcelain or other like ware. The upper end of this valve member is inverted 85 with walls 16 of a greater diameter returning on the walls of the pipe in inverted U-form, the return end of the pipe resting also in the cup, the edge of the inverted end extending substantially to the bottom. This valve member is open at each end and at 90 the lower end is attached the operating rod 4, so that as the rod is lifted it raises the valve partially out of the cup. The return end, 16, of the valve member is of such bulk that when the valve is at rest it displaces 95 enough water so that when it is elevated the water in the cup falls to a level whereby the air which is in the longer end of the siphon can escape between the inner wall of the end 16 and the outer wall of the valve member 15 and thence through aperture 3, or elsewhere. From the bottom of the upright portion 10 extends pipe 22 which connects to the jet orifice 23 of the bowl.

Normally the water in the tank is at the 110 level shown in Fig. 1, the water supply being controlled by a suitable ball-cock, and

the air is compressed in the long arm of the siphon and the upper end of the short arm. When rod 4 is lifted the valve member is also raised and the ends of the upset 5 walls 16 are lifted to a point just above the lowered level of the water in the cup. The air then escapes, as pointed out, and the siphon acts under natural laws, whereby the water in the tank passes up through the 10 short arm of the siphon, down through the long arm, through the valve member 15, filling the upright portion 10 of the seat or bowl member whence it flows through pipe 22 into the jet 23, thence outward through 15 the flush 20. It also rises to discharge through the rim outlets 21. The handle being dropped, the valve member returns to 20 its seat. When the water has been exhausted its level is below the lower end of the pipe 9 and the air rushes into the siphon through that pipe, filling the vacuum caused by the discharge and the water rising in 25 the tank compresses the air in the siphon when the apparatus is in condition for repeated operation. The annular cup 12 and the bowl are amply refilled after each operation by the water left standing in upright portion 10. This water flows into the bowl through the pipe 22 and through the 30 jet 23.

Having described my invention, what I claim as new and desire to secure by Letters Patent, is:

1. In a device of the character described, 35 a tank member having a siphon member mounted therein, and a vertically moving valve mounted in the siphon-discharge and adapted to coöperate with the siphon member to effect the flush through the bowl of 40 the device.
2. In a device of the character described, 45 a tank member having a siphon therein, one member of the siphon extending downwardly in an enlarged portion, a bowl portion having an upward extending chamber, the tank being adapted to be supported thereon, a cup-seal mounted in the said chamber to receive the extended arm of the siphon and a vertically movable valve 50 adapted to be sealed by the cup-seal and to

be opened to break the seal and effect discharge of the tank.

3. In a device of the character described, a bowl having in connection with the ordinary parts a rearward vertical chamber, a tank mounted relative to the said chamber, a siphon in the tank, a water-seal adapted to be supplied by the discharge from the tank, a valve in the chamber, the said siphon being extended into the water-seal, and the valve having a return portion extending into said seal, and of an enlarged bulk whereby to quicken the action of the siphon on lifting the valve, the said members co-operating on the lifting of the valve to 65 cause the flush of the device, substantially as shown.

4. A device of the character described, having a bowl portion with an upward extended chamber, a tank member positioned 70 for the discharge therefrom into the said chamber and having a siphon with one member extended into said chamber, and a valve adapted to control the operation of the siphon comprising a water-cup, the said 75 cup being mounted to be maintained by the discharge of the siphon in condition for operation of the valve, substantially as shown.

5. In a device of the character described, a siphon having one member extending 80 downwardly in an open-end portion, the said siphon also comprising a cup-seal receiving the said open-end portion and a vertically movable valve having an end extending into the cup-seal and adapted upon its 85 upward movement to operate the siphon, substantially as described.

6. A siphon comprising a fixedly mounted cup-seal, a depending member extending in an open end into the seal, a vertically 90 movable valve member depending into the cup-seal and adapted by the raising of the same to break the seal of the siphon, substantially as described.

In testimony whereof I affix my signature 95 in presence of two witnesses.

FREDERICK O. HILFIKER.
